UNITED STATES PATENT OFFICE

166,460

MOLDED PULP INSULATION ARTICLE

Richard S. French, Waterville, Maine

Application May 11, 1951, Serial No. 15,139

Term of patent 14 years

(Cl. D58—13)

To all whom it may concern:

Be it known that I, Richard S. French, a citizen of the United States, residing at Waterville, State of Maine, have invented a new, original, and ornamental Design for Molded Pulp Insulation Article, of which the following is a specification, reference being had to the accompanying drawing, forming part thereof.

Fig. 1 is a top plan view of a molded pulp insulation article, showing my new design;

Fig. 2 is a side view thereof;

Fig. 3 is a front elevational view thereof; and

Fig. 4 is a sectional view taken on the line 4—4 of Fig. 1.

What is claimed is:

The ornamental design for a molded pulp insulation article, as shown.

RICHARD S. FRENCH.
